(57) **CLAIM**

An ornamental design for a hospital bed rail pocket device, as shown and described.

DESCRIPTION

FIG. 1 is a front perspective view of my hospital bed rail pocket device in which the pocket flap is closed and the mounting strap is fully extended.

FIG. 2 is a front view thereof.

FIG. 3 is a left side view thereof in which the mounting position of the strap and a bed rail are both shown in chainline.

FIG. 4 is a top view thereof.

FIG. 5 is a bottom view thereof.

FIG. 6 is a rear view thereof.

FIG. 7 is a front view similar to FIG. 2 in which the flap is shown in an open position; and,

FIG. 8 is a front perspective view similar to FIG. 1 in which the flap is in an open position and a comb and eyeglasses, shown in broken line disclosure, are within the pockets. The broken line showing of the hospital bed rail pocket device is for illustrative purposes only and forms no part of the claimed design.
